UNITED STATES PATENT OFFICE.

THEODORE R. TREIBER, OF CHICAGO, ILLINOIS, ASSIGNEE, BY MESNE ASSIGNMENTS,
TO J. C. McFARLAND COMPANY, A CORPORATION OF ILLINOIS.

POCKET-BILLIARD TABLE.

1,367,440.

Specification of Letters Patent.

Patented Feb. 1, 1921.

Application filed June 28, 1919. Serial No. 307,323.

To all whom it may concern:

Be it known that I, THEODORE R. TREIBER, a citizen of the United States, residing at Chicago, in the county of Cook and State 5 of Illinois, have invented a certain new and useful Improvement in Pocket-Billiard Tables, of which the following is a full, clear, concise, and exact description, reference being had to the accompanying drawings, 10 forming a part of this specification.

My invention relates to pocket billiard tables and relates particularly to the ball return construction thereof.

One of the features of the invention relates to a return ball construction of simple character in which the balls will rarely, if ever, clog even though balls are returning from the several pockets simultaneously, or in quick succession.

20 The device includes as one of its essential features a vertical guide element for the returning balls, and another feature relates to the disposition of this vertical guide element within the inclosure of the sides of the 25 table whereby the device may be concealed and the symmetry of the table preserved. A feature supplemental to this relates to an arrangement of the parts whereby the structure is very simple and compact and has a 30 relatively small vertical dimension whereby the device is well adapted to be concealed within the inclosure of the sides of the table, the device retaining its non-clogging character nevertheless.

35 A further feature relates to a device of the above character in which the vertical guide element is inclosed within the sides of the table and which includes a runway adapted to receive balls from the vertical 40 guide element, said runway leading below the sides of the table to a visible point with respect thereto whereby, though the main portion of the ball return device is concealed, the balls may be observed returning from the 45 pockets without necessitating an aperture or cut in a side of the table which would detract from the appearance and add to the cost of manufacture of the table.

The above features and certain other features hereinafter appearing are embodied in 50 the preferred form of my invention herein-after fully described and illustrated in the accompanying drawings, and are effected by

certain novel constructions, combinations and arrangement of parts particularly 55 pointed out in the claims.

In the said drawings:

Figure 1 is a top plan view of a pocket billiard table embodying the features of my invention in their preferred form, the slates 60 and cushions being removed to more clearly illustrate the return ball structure.

Fig. 2 is a sectional side elevation of the same on the line 2-2 of Fig. 1 with the slates and cushions assembled thereon. 65

Fig. 3 is an enlarged partial sectional elevation on the line 3-3 of Fig. 2.

Fig. 4 is an enlarged sectional view in plan elevation on the line 4-4 of Fig. 3.

Fig. 5 is an enlarged partial sectional vertical elevation on the line 5-5 of Fig. 2. 70

Like characters of reference indicate like parts in the various views.

In the drawings, 1 indicates the sides of the table which are supported above the 75 supporting floor by legs 2 disposed at the corners and at the centers of the long sides of the table as is usual. Supported at the top of the sides 1 are the usual slates 3, and cushion rails 4, with cushions 5 attached thereto, are 80 secured to the edges of the slates, the cushions and cushion rails being cut out at the corners and at the centers of the long sides of the table to form ball pockets, as is usual. The upper portions of the sides and supporting structure of the table are cut away below these ball pockets, as designated at 85 6, see Figs. 1 and 2, to allow balls to drop down upon the upper ends of gulleys 7, which ends rest upon and are secured to respective horizontal flanges 8 of the supporting structure. An individual gully 7 is provided for each ball pocket, and they are all inclined downwardly therefrom and are disposed in superposed relation and extend 95 to points at one side of the table, preferably one of the short sides of the same. This individual gully construction is part of the subject matter of my co-pending U. S. application, Serial No. 330,302, filed October 100 13, 1919. The structure of the table illustrated herein is the subject matter of my co-pending U. S. application Serial No. 294,443, filed May 3, 1919, of which the first mentioned application is a division.

105 A vertical guide element 9 is disposed

within the inclosure of the sides 1 and has its upper end secured to a longitudinal girder 10 disposed at the top of the sides of the table and extending across the space 5 inclosed by said sides, as above stated the gullies 7 are inclined downwardly from their respective ball pockets, and the lower ends thereof are disposed in different horizontal planes. The vertical guide element 10 9 is preferably a tube with apertures 11 cut therein at intervals, see Fig. 3, through which communication is established, between the vertical guide element and the lower ends of the gullies. The lower end of each 15 gully leads to a respective aperture 11, and this lower end is supported by the metal displaced from the aperture which is turned outwardly from the lower portion of the aperture, as designated at 12, see Fig. 3. 20 The vertical guide element 9 is preferably disposed adjacent one short side of the table and the center portions of the longer gullies are supported by metal straps 13 having their middle portions extending underneath 25 the respective gullies and having their ends secured to respective cross girders 14 disposed at the top of the sides of the table and extending across the space between opposite sides of the same. The center portions 30 of the gullies leading from the pockets nearest adjacent the vertical guide element 9 are supported by respective brackets 15 secured to and extending from the inner face of the adjacent side 1 of the table. 35 All these parts are preferably secured together by welding.

By reason of the fact that the lower ends of the gullies are disposed in different horizontal planes it is impossible that a number 40 of balls entering the vertical guide element simultaneously from different gullies can bridge the same and thereby block the passage. See Fig. 3 in which balls 16 are shown entering the vertical guide element from different gullies simultaneously, and it will be 45 noted that, if the balls do strike one another before they are fully entered into the vertical guide element, the blow will be a glancing one and the balls will not clog as a result thereof.

As above set forth the lower ends of the gullies are disposed in different horizontal planes. In addition, see Figs. 1 and 4, the gullies communicate with the vertical guide element on different sides of the same, whereby, when, as shown, all of the gullies communicate with a single vertical guide element, the device may be disposed within a comparatively small vertical dimension, 55 and be effectually concealed within the usual sides 1 of the table where the vertical guide element is disposed within the sides of the table, the device retaining its non-clogging character as above set forth. In the 60 preferred embodiment the gullies commun-

icate with the vertical guide element on different sides of the same and in non-parallel relation whereby, if, as shown, the vertical guide element is formed to maintain the balls in a single row, a ball, passing downwardly in the vertical guide element, strikes another ball entering the same from one of the gullies, the axes of rotation of the balls as occasioned by them rolling down their respective gullies are not parallel and for this 75 reason the balls squirm with relation to one another, thus further preventing them from clogging.

The vertical guide element 9 is preferably of such a diameter, *i. e.*, less than the sum 80 of the diameters of two balls, that two balls cannot pass each other therein whereby the balls are forced to drop in a single row therethrough. One side of the lower end of the vertical guide element 9 is turned 85 horizontally across the inclosure of the guide element, as designated at 17, and the opposite side of the lower end thereof is cut away to form an opening, as designated at 18, see Fig. 3, to allow balls to pass out of the 90 guide element. One end of a runway 19 rests on and is welded to the horizontally turned portion 17, and is adapted to receive balls from the guide element and leads therefrom, preferably inclining downwardly, below the adjacent side of the table to a visible point with respect thereto. The runway is supported by suitable brackets 20 secured to and extending from the adjacent side 95 of the table. The end of the runway opposite that which receives balls from the guide element is disposed above a usual basket 21 to guide balls therein.

The gullies 7 and runway 19 are similar in construction and the structures thereof are formed of sheet metal bent, see Fig. 4, to provide parallel spaced upwardly facing channels 22 in which are secured rails 23, of rubber or other suitable material, upon which balls 24 run. Certain portions of the 105 gullies and runway are curved as will be observed, and the sheet metal structure of the same is extended upwardly of the rails on the outsides of these curves, as designated at 25, to prevent the balls jumping off the rails. The vertical guide element 9 is 110 lined with hard rubber, as designated at 26, to prevent marring of the balls, this lining being apertured at the openings 11 of the 115 guide element for obvious reasons.

It will be noted further that where the vertical guide element is inclosed within the sides of the table, the runway may be, and is in the preferred embodiment, led below the adjacent side of the table to a visible point with respect thereto to allow the balls to be observed as they return from the various pockets without necessitating the sides of the table being apertured or cut.

The vertical guide element allows the gul- 130

lies and runway to be very gradually inclined whereby the balls may proceed slowly thereon and enter the vertical guide element at a slow speed thus facilitating the assembly 5 of the balls into a single row in the guide element as shown in the preferred embodiment.

While I have herein shown and particularly described the preferred embodiment of 10 my invention I do not wish to be limited to the precise details of construction shown as changes may readily be made without departing from the spirit of my invention, but having thus described my invention I claim 15 as new and desire to secure by Letters Patent the following:—

1. A game table including a plurality of individual gullies, each leading from a respective ball pocket of the table and inclined 20 downwardly therefrom, the lower ends of said gullies being disposed in different horizontal planes, and a vertical guide element 25 communicating with the lower ends of said gullies to receive balls therefrom.

2. A game table including a plurality of individual gullies, each leading from a respective ball pocket of the table and inclined downwardly therefrom, the lower ends of 30 said gullies being disposed in different planes, and a vertical guide element communicating with the lower ends of said gullies to receive balls therefrom and disposed within the inclosure of the sides of the table.

3. A game table including a plurality of 35 individual gullies, each leading from a respective ball pocket of the table and inclined downwardly therefrom, the lower ends of said gullies being disposed in different horizontal planes, and a vertical guide element 40 formed to maintain balls passing therethrough in a single row and communicating with said lower ends of said gullies to receive balls therefrom.

4. A game table including a plurality of 45 individual gullies, each leading from a respective ball pocket of the table and inclined downwardly therefrom, the lower ends of said gullies being disposed in different horizontal planes, and a vertical guide element 50 disposed within the inclosure of the sides of the table and formed to maintain balls passing therethrough in a single row and communicating with said lower ends of said gullies to receive balls therefrom.

5. A game table including a plurality of 55 individual gullies, each leading from a respective ball pocket of the table and inclined downwardly therefrom, the lower ends of said gullies being disposed in different horizontal planes, a vertical guide element 60 formed to maintain balls passing therethrough in a single row and communicating with said lower ends of said gullies to receive balls therefrom, and a runway communicating with the lower end of said ver-

tical guide element and adapted to receive balls therefrom.

6. A game table including a plurality of individual gullies, each leading from a respective ball pocket of the table and inclined 70 downwardly therefrom, the lower ends of said gullies being disposed in different horizontal planes, a vertical guide element disposed within the inclosure of the sides of the table and formed to maintain balls passing 75 therethrough in a single row and communicating with said lower ends of said gullies to receive balls therefrom, and a runway communicating with the lower end of said vertical guide element and adapted to receive 80 balls therefrom, said runway leading below one of the sides of the table to a visible point with respect thereto.

7. A game table including a plurality of individual gullies, each leading from a respective ball pocket of the table and inclined 85 downwardly therefrom, the lower ends of said gullies being disposed in different horizontal planes, and a vertical guide element 90 communicating with said lower ends of the gullies to receive balls therefrom, said lower ends of the gullies being disposed to communicate with said guide element on a plurality of sides of the same.

8. A game table including a plurality of 95 individual gullies, each leading from a respective ball pocket of the table and inclined downwardly therefrom, the lower ends of said gullies being disposed in different horizontal planes, and a vertical guide element 100 disposed within the inclosure of the sides of the table and communicating with said lower ends of the gullies to receive balls therefrom, said lower ends of the gullies being disposed to communicate with said guide element on a 105 plurality of sides of the same.

9. A game table including a plurality of individual gullies, each leading from a respective ball pocket of the table and inclined 110 downwardly therefrom, the lower ends of said gullies being disposed in different horizontal planes, and a vertical guide element, formed to maintain balls passing therethrough in a single row and communicating with said lower ends of the gullies to 115 receive balls therefrom, said lower ends of the gullies being disposed to communicate with said guide element on a plurality of sides of the same.

10. A game table including a plurality of 120 individual gullies, each leading from a respective ball pocket of the table and inclined 125 downwardly therefrom, the lower ends of said gullies being disposed in different horizontal planes, and a vertical guide element disposed within the inclosure of the sides of the table and formed to maintain balls passing therethrough in a single row and communicating with said lower ends of the gullies to receive balls therefrom, said 130

lower ends of the gullies being disposed to communicate with said guide element on a plurality of sides of the same.

11. A game table including a plurality of 5 individual gullies, each leading from a respective ball pocket of the table and inclined downwardly therefrom, the lower ends of said gullies being disposed in different horizontal planes, and a vertical guide element 10 formed to maintain balls passing therethrough in a single row and communicating with said lower ends of the gullies to receive balls therefrom, said lower ends of the gullies being disposed to communicate 15 with said guide element on a plurality of sides of the same and disposed in non-parallel relation with each other.

12. A game table including a plurality of 20 individual gullies, each leading from a respective ball pocket of the table and inclined downwardly therefrom, the lower ends of said gullies being disposed in different horizontal planes, a vertical guide element formed to maintain balls passing 25 therethrough in a single row and communicating with said lower ends of the gullies to receive balls therefrom, said lower ends of the gullies being disposed to communicate with said guide element on a plurality of

sides of the same and disposed in non-parallel 30 relation with each other, and a runway communicating with the lower end of said vertical guide element and adapted to receive balls therefrom.

13. A game table including a plurality of 35 individual gullies, each leading from a respective ball pocket of the table and inclined downwardly therefrom, the lower ends of said gullies being disposed in different horizontal planes, a vertical guide element 40 disposed within the inclosure of the sides of the table and formed to maintain balls passing therethrough in a single row and communicating with said lower ends of the gullies to receive balls therefrom, said 45 lower ends of the gullies being disposed to communicate with said guide element on a plurality of sides of the same and disposed in non-parallel relation with each other, and a runway communicating with the lower end of said vertical guide element and adapted to receive balls therefrom, said runway leading below one of the sides of the table to a visible point with respect thereto.

In witness whereof I hereunto affix my 55 signature this 23rd day of June, A. D. 1919.

THEODORE R. TREIBER.
